MECHANICAL PENCIL

Lucifer J. Most, Hudson County, N. J.

Application March 18, 1939, Serial No. 262,591

2 Claims. (Cl. 120—18)

My invention relates to a mechanical pencil, and is a modification of the structure as disclosed in my pending application, Serial No. 209,739, filed May 19, 1938.

5 The object of the invention is to provide a simple mechanism, formed of few moving parts, for propelling, retracting, expelling and automatically presenting a new lead to writing position.

10 Another object of the invention is to provide a mechanical pencil in which the lead itself is a part of the feed mechanism.

A still further object of the invention is to provide a mechanical pencil where the feeding 15 can be done generally with the fingers holding the pencil in writing position.

In the appended drawing, forming part of this application, Figure 1 is a fragmentary elevation, partially in section.

20 Figure 2 is an enlarged cross-section on line 2—2, Figure 1.

Figure 3 is an enlarged cross-section on line 3—3, Figure 1.

Figure 4 is an enlarged cross-section on line 25 4—4, Figure 1.

Figure 5 is a section through the die and guiding tubes on line 5—5, Figure 4.

Figure 6 is a fragmentary elevation of a modified form of the pencil end, as shown in Figure 1, and

30 Figure 7 is a section on line 7—7, Figure 6.

Referring to the drawing, 10 is the pencil shell or barrel formed with a hollow tip 11, terminating in an opening 12, through which a lead may protrude. The tip 11 is provided with lateral cut-outs or openings 13 which are diametrically opposite, and through which the nut or die 14 is accessible for manipulation.

40 The die is maintained in proper register with the openings 13 by spaced tubular members 15 and 18 of angular cross-section, corresponding to the angular cross-section of the lead they are to engage, in this particular case the lead being square. The lower tube 15 is anchored in the tip 11 by a washer plug 16.

45 The die 14 has a circular recess 17 which houses a portion of the tube 15, permitting the die to revolve freely relative to said tube. A similar recess 17 is formed on the opposite end 50 of the die 14 to accommodate the lower end of the tubular member 18, the upper end of the tubular member 18 terminating with a hopper 19, which constitutes the body of the magazine for leads formed by the hopper with the bar-

55 rel 10.

5 It will be seen that the die 14 positioned between the spaced tubular members 15 and 18 is free to revolve relatively to said tubular members, but prevented from moving longitudinally thereof, and is maintained by said tubular members in proper register with the lateral openings 13 in the barrel. To assure proper axial and angular alignment of the two tubular members 15 and 18, a washer 20 is provided between the tubular member 18 and the interior of the tip 11.

The threaded portion 21 of the bore of the die lying between the recesses 17 is formed to engage the corners of the lead, which is presented thereto by the tube 18. This tube, due 20 to its cross-section, prevents the lead from turning when the die 14 is revolved relatively thereto, and as the lead progresses through the die it will enter the lower tubular member 15, which aligns with the tube 18; as the lead progresses through the tube it can pass through the opening 12 in the tip 11. To prevent a lead section 22 passing beyond the die 14 from dropping out from the tubular member 15, the lower end of the tube or of the tip is made to frictionally 25 engage the lead therein, and the advancing of that section of the lead, which remains in the tube 15, is obtained through the succeeding lead which passes the die 14 to enter the tube 15.

The position of the die 14 being such that it 30 lies in proximity of the fingers engaging the pencil in writing position, the manipulation of the lead in the pencil, therefore, can be done by the fingers while in that position.

In the modified form shown in Figures 6 and 35 7, the shoulders of the lateral apertures 13' are rounded up inwardly to provide a better access to the die 14 by flattening and rounding off the shoulders of the lateral openings 13'.

I claim:

1. In a mechanical pencil, a barrel having a lead outlet, a pair of aligning spaced tubular members of angular cross-section fixed in the barrel in proximity of the outlet and aligning therewith, a threaded die positioned between the 45 tubular members and having annular recesses accommodating the proximate ends of the tubular members, so that the said die is free to revolve relatively to said members, but prevented from moving longitudinally, said barrel having 50 lateral openings giving access for the manipulation of the die, and a hopper rising from the tubular member above the die forming with the barrel the magazine for leads.

2. In a mechanical pencil, a barrel terminat-

55

5 ing with a tip, a pair of spaced aligning tubular members of angular cross-section located in said tip and co-axial therewith, a threaded die positioned between the tubular members co-axial therewith and having an annular recess accommodating the proximate ends of the tubular members so that this said die is free to revolve relatively to said tubular members, but prevented

from longitudinal movement thereof, said tip having means whereby access may be had to said die from the lateral side of said tip, and a hopper forming part of the upper tubular member in the tip, and engaging the barrel to a lead magazine. 5

LUCIFER J. MOST.
